UNITED STATES PATENT OFFICE.

JAMES E. MURPHY, OF MIDWEST, WYOMING.

STEEL DERRICK OR STEEL TOWER.

Application filed December 11, 1924. Serial No. 755,307.

The invention relates to improvements in a steel derrick.

It is an object of the invention to provide a derrick or tower structure composed entirely of steel free of connecting bolts, rivets or the like.

It is a further object of the invention to provide a tower in which the angle irons, braces and girth connections all interlock 10 to tightly unite the various parts of the tower structure to permit the same to be readily constructed and eliminate the use of bolts, rivets, etc.

In the drawings Figure 1 is a view in 15 side elevation showing a tower constructed in accordance with my invention, with parts broken away. Fig. 2 is a sectional view showing the arrangement of the cross girders and tie rods. Fig. 3 is a detailed view showing 20 the method of connecting the cross girders and Fig. 4 is a view similar to Fig. 3 showing the method of applying tie rods.

Referring now more particularly to the drawings, wherein like reference characters 25 indicate corresponding parts, the numeral 1 designates the angle irons forming the tower. Four of these irons are used as shown in Figure 2 of the drawings. The irons are preferably arranged so that they 30 converge toward their upper end providing a relatively large base and a relatively narrow tower portion. The structure is also provided with transverse connecting girders 3 and interposed crossed tie rods or braces 35 4. The girders 3 are disposed between each pair of angle irons and are connected thereto in the manner to be now described. Inasmuch as the connection between each girder and angle iron, as well as the braces, is identical, a consideration of one will suffice for all. Each angle iron, therefore, has a slot 4 in one side and an elongated slot 5 in the other arm thereof. The girders 3 are preferably of a cylindrical form intermediate 45 their ends, having at the ends thereof, however, flattened portions 7 and 8, the flattened portion 7 of one girder being provided with a slot 9 opening from the bottom thereof, while the flat portion of the girder 8 is formed with a slot 10 opening from the top, the two girders being adapted to be interlocked, as the slots do not extend entirely through the flattened portions. The flat

portion of each girder is also formed with a connecting notch 11 in the upper corner 55 thereof to which hooked ends of the brace rods 4 are connected for purposes which will now appear.

In erecting the scaffold structure the girders on the opposite side of an angle iron 60 are first inserted to occupy the position shown in Figure 3. In this position the flattened part 7 of one girder is at the upper end of the elongated slot and lies above the flattened portion of the lower girder. This 65 upper flat portion of the girder is then lowered to the position shown in Figure 4 interlocking with the lower girder. The ends of the brace rods 4 are placed within the notches 11 in the upper corners of the flat 70 portion of each girder. This holds the girders in an interlocked position. The lower ends of the brace rods 4 each connect with the angle irons by having hooked end portions enter apertures 12 therein so that one 75 end of each brace is connected directly with an angle iron and the other end interlocked around one of the extended flat portions of the connecting girders.

It will be understood that the present disclosure is merely for the purpose of illustration and that the construction of the leg shown as an angle iron and the braces in the girders can be materially modified without departing from this invention.

Having thus described my invention, what I claim is:

1. A tower structure comprising a plurality of legs, each of angle iron formation, each angle portion of each leg being provided with a plurality of apertures, the aperture in one portion extending beyond the other, connecting girders disposed between said legs, said girders being provided with extensions projecting through the 90 apertures in the angle portion of the legs, interlocking means carried by the adjacent girders for locking said girders together after passage through the apertures in each of said legs, and means for retaining said 95 girders in an interlocked position.

2. A tower of the character described, comprising a plurality of legs, each of an angle iron formation, transverse girders connecting said legs, interlocking means carried by adjacent cooperating girders, each 100

passing through an aperture in one of said legs, and means for retaining said girths in an interlocked position.

3. A tower of the character described, comprising a plurality of legs, each of an angle iron formation, transverse girths connecting said legs, interlocking means carried by adjacent cooperating girths, each

passing through an aperture in one of said legs, and means for retaining said girths in an interlocked position, comprising tie rods each having one end connected with a girth and the opposite end with one of said legs. ¹⁰

In testimony whereof I affix my signature.
JAMES E. MURPHY.
